UNITED STATES PATENT OFFICE.

T. S. HEPTINSTALL, OF MENDOTA, ILLINOIS.

IMPROVEMENT IN GANG-PLOWS.

Specification forming part of Letters Patent No. 26,587, dated December 27, 1859.

To all whom it may concern:

Be it known that I, THOMAS S. HEPTINSTALL, of Mendota, in the State of Illinois, have invented a new and useful machine or implement to plow two or more furrows of land at the same time, and which implements are commonly called "gang-plows;" and I do hereby declare that the following is a full, clear, and exact description of the construction and operation of the same, reference being had to the annexed drawings, making a part of this specification.

Figure 1 is a perspective view; Fig. 2, longitudinal elevation; Fig. 3, a transverse section, and Fig. 4 a plan.

One of the wheels, A, is placed in the front or fore part of the plow, and each of the other two wheels, B B, is placed on one side of the latter part or end of the plow. The front wheel, A, is a caster-wheel placed at the end of an upright shaft, C, fixed on a spindle, S, fastened to two of the beams Q Q of the plow. This upright shaft C is extended upward above the spindle S, and is joined by the means hereinafter mentioned to the other two wheels, B B, and the lever-power hereinafter described. The two wheels B B near the end of the plow turn on crank-axes X X, fixed at the lower part of the shafts D D, made firm on and suspended from a movable spindle, E, that extends across the four beams of the plow and works in boxes Y Y, fixed on the two outside beams, P P. To this spindle E a triangle, F, that extends upward from it, is firmly attached. The shaft C first described is connected with this triangle F by a rod, G, one end of which rod is fastened to the upper part of the shaft C, and the other end of the rod is fastened to the upper part of the triangle F at R. Thus the front wheel, A, and hind wheels, B B, by means of the front shaft, C, the rod G, the triangle F, its spindle E, and the hind shafts, D, and their crank-axes X, are connected with each other, and the triangle F and hind shafts, D

D, being fastened to and made firm on the hind spindle, E, the action of the front wheel, A, and the hind wheels, B B, is mutually dependent and regulated by the action of each other. Part of the upper side of the triangle F is hollow, and it is supported by the side of the triangle which is nearest the end of the plow. When required, a lever-pole, H, is inserted into this hollow part of the triangle, and by means of this lever the plowman at will can raise the plows out of the ground and above it, or lower the plows into the ground and at pleasure regulate their depth in it.

By means of the regulator I, in which the triangle moves, and the adjusting-pin, the plows can be fixed at the height or depth that from time to time is required, and the lever-pole H can then be unshipped and put out of the plowman's way and laid ready for use when wanted.

The rollers or wheels K K are placed behind the first and last plows and on a level with the bottoms of them. These rollers K K are intended to press against the unplowed ground and counteract the tendency of the plows to work sidewise, and they will give steadiness to the working of the plows and make the work precise, regular, and excellent. These rollers K K will enable the landside of the plows to be dispensed with, and the power will be saved that is required to overcome their friction.

The nature of the invention consists of economizing labor, expense, and time in plowing land.

What I claim as my invention, and desire to secure by Letters Patent, is—

The arrangement of the wheels A B B, shafts C and D D, spindle E, triangle F, rod G, lever-pole H, regulator I, and rollers K K, as described, for the purposes herein set forth.

T. S. HEPTINSTALL.
